DRILLING MACHINE

Andrew T. Dupont, Washington, D. C.

Application February 13, 1928, Serial No. 254,035
Renewed February 11, 1933

30 Claims. (Cl. 121—5)

My invention relates to drilling machines and particularly to the means for feeding the mechanism and rotating the drill steel.

One object of my invention is the provision of improved means whereby the drill steel may be rotated automatically.

Another object of my invention lies in an improved construction wherein the feed piston is used as one of the elements for rotating the drill steel.

A further object of my invention consists in the use of a single motor for both feeding the mechanism to the work and rotating the drill steel.

Still another object of my invention is the provision of improved means for automatically controlling the feeding of the mechanism and the rotation of the drill steel.

Other objects of my invention will become more apparent in the following disclosure and in the accompanying drawing wherein one embodiment of my invention is clearly illustrated.

In the drawing:

Fig. 1 is a side elevation of the machine with parts shown in section.

Fig. 2 is a partial section of Fig. 1 showing the automatic control valve in a position different from that shown in Fig. 1.

Fig. 3 is a section through line 3—3 of Fig. 1.

Fig. 4 is an end elevation of the machine viewed from the right hand side of Fig. 1.

Figs. 5 and 6 indicate sectional details of one of the three-way valves, shown in Fig. 1.

Fig. 7 shows a modification.

Referring first to the general arrangement of parts as illustrated in Fig. 1, 1 is the support for the machine generally adapted to be mounted on a suitable tripod or mine column; 2 is the hammer cylinder provided with the usual hammer piston, or anvil 3; the drill steel 4, having a passage 5 therethrough for the passage of a cleansing fluid as is customary; and the valve chest 6 to which air is admitted by means of the pressure fluid pipe 7; 8 is the feed cylinder; 9 is the feed piston.

Intermediate the hammer cylinder 2 and the feed cylinder 8 is the guide plate 10, which guide plate is slidingly mounted upon the guide-ways 11 provided on the support 1. The piston 9 of the feed cylinder is provided with a rearwardly projecting shank or piston rod 12, which has rigidly fixed to its rear end the rod 13 carrying a cross-head 14. The cross-head is rigidly secured to the support 1 by means of a pair of connecting rods 15. A pin 16 is driven through the piston rod 12 and the rod 13 and another pin 16 is driven transversely through the cross-head and the rod

13. By means of this construction, it will be seen that the piston rod 12 and the feed piston 9 are prevented from either rotation or translation, and that the feed cylinder and the hammer cylinder mounted thereon may be fed back and forth, depending upon to which side of the feed piston 9 pressure fluid is applied. The drill steel 4 is mounted for reciprocation in the chuck 17. This chuck carries at its forward end the spur gear 18, which meshes with a gear 19 mounted upon a stub shaft 20 upon which it is free to slide. The gear 19 is driven from the gear 21 mounted upon the shaft 22 mounted for rotation in the front head 23 of the feed cylinder. The portion of the shaft 22 which projects into the feed cylinder is provided with a reversible thread 24 adapted to cooperate with an internal thread cut into the piston 9 so that the relation between the piston and the threaded part 24 is that of nut and screw. For the sake of clearness the threaded part 24 will hereinafter be referred to as a screw. A disk or guide 25 is provided at the extremity of the screw 24 and the space in the hollow piston 12 between the disk 25 and the piston 9 is packed with a suitable lubricant. It will be seen that by this arrangement when pressure fluid is supplied to the feed cylinder the screw 24 which is secured to the feed cylinder moves with the latter and is caused to rotate, since the piston is held fast, and that this rotation is transmitted to the drill steel through the intermediate gears at the front of the machine. These gears are securely maintained in position by means of the plates 25 and 26, the outer plate 26 serving as the outer bearing for the stub shaft 20 and the shaft 22. The plate 26 is held in position by means of connecting rods 27 extending between such plate and the rear head 28 of the hammer cylinder. A resilient buffer 29 is interposed between the cross head 14 and the rear head 30 of the feed cylinder.

Pressure fluid is admitted to the feed cylinder on each side of the feed piston through passages 30, 31 which receive the fluid from a pipe 32 connected with the main air inlet 7. Between the passages 30, 31 and the pipe 32 there is interposed a casing 33 which contains the automatic control valve designated generally at 34. The casing 33 is preferably cast integrally with the hammer cylinder, although it may be mounted thereon by any suitable means. It is cylindrical in general appearance and is drilled to provide a suitable bore for the valve 34.

A solid wall 35 forms a back for the casing 33 and a cover plate is provided at 36 so as to en-

close the valve. A port is indicated at 37 into the back wall 35, the purpose of which will appear later. The pipe 32 opens into the casing 33 through two branches 38 and 39, each of which 5 carries a rotary three-way valve indicated respectively at 40 and 41. These valves are identical in construction and a section of one of them is shown in Figures 5 and 6. When the valve plug 42 is in the position indicated in Fig. 5, 10 through passage is provided for the pressure fluid from the source to the valve casing 33 whereas then the plug 42 is given a quarter turn in a clockwise direction as shown in Fig. 6, admission is blocked by the plug 42 and exhaust occurs 15 through a port 43 provided in the valve casing. Passage 39 opens into the casing 33 in the same plane as the port opening of pipe 39, while passage 31 also opens into casing 33 in the same plane as the port opening of pipe 38. The valve 34 20 comprises four spools or heads of which the left-hand spool has the greatest diameter, while the three remaining spools 45, 46, and 47, have the same diameter. It will be noted that the passage 39 communicates with pipe 39 through the space 25 in the casing 33 provided between spools 46 and 47, while passage 31 communicates with pipe 38 through the space in the casing 33 provided between spools 45 and 46. It will further be noted that the space separating spools 45 and 46 is 30 greater than that separating spools 46 and 47. The reason for this design will appear later. Spool 47 is provided with a passage 48 extending radially to the periphery of the spool. This 35 passage communicates with another passage 49 at right angle thereto leading to the space between the spool 47 and the back wall 35. Into the large spool 44 are mounted stud bolts 50 extending through suitable apertures 51 in the cover 36 which are of such diameter that sliding motion 40 of the stud bolts therethrough is free.

Between the inner side of the cover 36 and the end face of spool 44 springs 52 are mounted around each stud bolt 50 and nuts 53 are provided at the end of the bolts outside of casing 33, 45 so that the tension of the springs may be adjusted and varied, and the valve 34 may be properly located in its casing with respect to the ports and passages which it controls. In addition to serving as a mounting for the springs 52 the stud bolts 50 also serve to prevent rotation of the valve 34 and to guide it in its motion of translation. A small shoulder is provided at 54 in the casing 33 so as to limit movement of valve 34 50 in its travel in the right-hand direction. A passage 55 is shown having a port opening into the forward end of the feed cylinder 8, while its other extremity opens into the casing 33 in the space between spools 44 and 45.

The mode of operation of my invention is as 60 follows:

When the main valve (not shown) on the air inlet pipe 7 is open, pressure fluid is admitted to the valve casing 6 wherein the usual automatic valve controls its distribution to the hammer cylinder for operating the hammer piston. At the 65 same time pressure fluid flows through pipes 32, 38, 39 into the valve casing 33. At this time, both valves 40, 41, are in the position shown in Fig. 5 and the fluid passes between spools 45, 46, into 70 passage 31 and is admitted in the rear of the feed cylinder. The fluid also flows into the space between spools 46 and 47, passage 30 and is admitted into the forward end of the feed cylinder. Since the forward face of the feed piston 9 is 75 larger than the rearward face thereof, the feed

cylinder and the hammer cylinder carried thereon move in a forward direction. The screw 24 being carried by the feed cylinder moves therewith away from the stationary feed piston and in so doing is caused to be rotated through the nut and screw engagement between the piston 9 and the screw 24. This rotation is transmitted from gear 21 to pinion 19 and from the latter to the gear 18. This gear 18 being fast on the chuck 17 will cause the latter to rotate and also the drill steel 4 carried thereby into interlocking relation. Therefore, as long as the feeding means is operated the drill steel will be rotated. The pressure fluid admitted into the forward end of the cylinder through passage 30 will also find its way 15 through passage 55 and into the space in the valve casing 33 comprised between spools 44 and 45. Since spool 44 is larger in diameter than spool 45, a certain pressure will be exerted against spool 44, tending to push it towards the left in Figs. 1 and 20 2, and to overcome the pressure of springs 52. The pressure of these springs is so adjusted by means of the stud bolts 50 and nuts 53, or by the judicious selection of springs of the desired strength, that it balances the pressure of the fluid 25 on the right-hand side of spool 44 during normal running operations so that the valve 34 assumes the position shown in Fig. 1.

If, due to the nature of the ground, the drill 30 steel should become stuck, rotation of gears 18, 19 and 21, will be interrupted and these gears will lock. The rotation of screw 24 which through the shaft 22 is keyed to gear 21, will also stop. As soon as this occurs the fluid admitted into the forward end of the feed cylinder will be unable 35 to continue the forward feed since the feed cylinder will be locked to the feed piston through nut and screw engagement between the feed piston 9 and the screw 24. Therefore, the pressure in the forward end of the feed cylinder will increase 40 and this pressure rise will be transmitted through passage 55 into the space between spools 44 and 45 of the valve 34, where, acting against spool 44, it will overcome the pressure of springs 52 causing the valve 34 to shift to the position indicated in Fig. 2.

When the valve 34 is in this position, the spool 47 thereof closes port opening of pipe 39, so that fluid admission to passage 30 and the forward end of the feed cylinder ceases. At the same time 50 passage 48 in spool 47 coincides with the port opening of passage 30 and exhaust occurs from the forward end of the feed cylinder, through passages 30, 48, 49 and through the port 37 in the wall 35 into the atmosphere. The space between 55 the spools 45 and 46 is such that when the valve 34 is in the extreme left-hand position shown in Figure 2, admission of pressure fluid from pipe 38 to passage 31 and the rear end of the cylinder is continued. Therefore, as soon as the pressure 60 in the rear end of the feed cylinder overcomes that in the front end thereof, the tendency is for the feed to be reversed and the screw 24 to be rotated in the opposite direction. This will cause the drill steel to be rotated in the opposite direction and to free itself from the seam. During 65 this period of feed retraction and reversal of rotation, the valve 34 will be maintained in the position shown in Figure 2, not only by the pressure fluid against spool 44 but also by the exhaust 70 pressure of the fluid against the end spool 47, which helps to delay the return of the valve. As soon, however, as these pressures, as well as the pressure in the forward end of the cylinder, have fallen to a considerable extent, the springs 52 75

will shift the valve 34 back to its normal position shown in Figure 1, and forward feed and normal drill steel rotation will be resumed. Should the steel again become stuck when it reaches its outermost position, the conditions described above will again obtain, that is, the feed and rotation will be reversed and then returned to normal. This will occur several times until the obstruction is completely cleared. It may be desirable at times to prevent rotation of the steel, such for instance, as when spotting the hole or when retracting the feed. This may be accomplished by sliding the pinion 19 on shaft 20. For this purpose pinion 19 is provided with an extension 55 in which a groove 56 is provided. A fork 57 straddles this groove and is provided with a suitable handle (not shown) extending through casing 26 for manipulation. If desired, a speed gear shift of the type shown in United States patent to Kimmman No. 639,737 of 1899, may be used, so that the drill steel may be rotated at different speeds. It will be understood, of course, that the pitch of thread on screw 24 as well as the sizes of gears 18, 19 and 21, will be judiciously chosen so that the efficiency of the combined feeding and rotating means will be as high as possible.

When the tool has been driven to the work as far as the length of the drill will permit or when the feed cylinder has reached the end of its forward movement, valve 41 will be turned in the position shown in Fig. 6, so that the forward end of the feed cylinder will exhaust through passage 30, valve plug 42 and exhaust port 43. The feed is maintained in the rearward cylinder end so that the feed cylinder and the hammer cylinder will be retracted. When it is desired to exhaust both the forward and rearward ends of the feed cylinder, both valves 40 and 41, are turned to the exhaust position shown in Fig. 6.

In order to maintain valve 34 in the position shown in Fig. 2, for some time after the pressure in the forward feed cylinder end has fallen below that in the rearward feed cylinder end, a dash-pot system such as shown in Fig. 7, may be used. In this figure valve casing 33 is provided with an additional chamber 58, containing oil or other suitable liquid. A piston 59 having a restricted port 60 therethrough is adapted to travel in this chamber and is connected by means of a stem 61 with the valve 34. A wall 62 separates chamber 58 from the chamber in which valve 34 is located. When, the rotation of the drill steel is prevented, the valve 34 is moved from the position shown in Figure 1 to that shown in Fig. 2, as explained above, causing exhaust of the forward cylinder end and of the space between spools 44 and 45. Due to the dash-pot arrangement, it will take some time for the valve 34 to resume its normal position and during this time the pressure fluid in the rear feed cylinder end will reverse the direction of feeding motion and the rotation of the drill steel. Delay of the return of valve 34 to its normal position is also increased, as in Figures 1 and 2, due to the pressure of the exhaust fluid acting against the end spool 47. The return of valve 34 to normal position may be differently timed depending on the size of port 60 and means well known in the dash-pot art may be used to vary the size of the leak port at will.

The advantages of my invention will be readily apparent to one skilled in the art to which it appertains. Heretofore, two separate motors have been used, one to rotate the tool and another and separate motor for feeding it to the work. Where

my invention is used, a single motor performs both operations. Furthermore, in embodying my automatic control valve in a drilling machine, men who have heretofore had to manually release the stuck drills with all the delay incident thereto, may be free to perform other work. A single workman may supervise a whole battery of the machines equipped with my invention.

While I have in this application specifically described two forms which my invention may assume in practice, it will be understood that these forms of the same are shown for purposes of illustration and that the invention may be modified and embodied in other forms without departing from its spirit or the scope of the appended claims.

What I claim is:

1. In a drilling machine, a hammer cylinder, a pneumatic hammer therein, a drill steel operated by said pneumatic hammer, feeding means for said steel comprising a feed cylinder, a stationary hollow feed piston therein, a member in said piston having therewith a nut and screw connection, connecting means between said member and said drill steel including a clutch and means for admitting pressure fluid to the feed cylinder whereby feeding and rotating the steel occurs simultaneously, or feeding occurs independently, at the will of the operator.

2. In a drilling machine, a hammer motor, a motor for feeding said hammer motor comprising two relatively movable elements, a member connected to one of said elements and having a nut and screw engagement with the other of said elements so that upon relative motion between said elements the member is rotated and means for connecting and disconnecting at will the member with the drill steel to rotate the latter when the member rotates, said last named means being independent of the hammer motor.

3. In a drilling machine having a drill steel therein, means for feeding and rotating the steel in one direction, and means responsive to resistance to rotation for automatically reversing the direction of feed and of rotation.

4. In a drilling machine, a hammer motor, a drill steel operated thereby, a single motor for feeding and rotating said drill steel and means responsive to resistance to rotation for reversing said motor.

5. In a drilling machine, a hammer motor, a drill steel operated thereby, a single motor for feeding and rotating said drill steel and means responsive to pressure conditions in said single motor caused by sticking of the drill steel for reversing the latter.

6. In a drilling machine, a hammer motor, a drill steel operated thereby, a motor for feeding and rotating the drill steel comprising a cylinder and a piston, means for simultaneously admitting pressure fluid on each side of said piston, and means responsive to resistance to rotation for interrupting admission of pressure fluid to one side of said piston.

7. In a drilling machine, a hammer motor, means for feeding said hammer motor to the work comprising a cylinder and a piston, means for simultaneously admitting pressure fluid on each side of said piston and means responsive to pressure conditions on one side of said piston for interrupting admission of pressure fluid to the said side of the piston.

8. In a drilling machine, a hammer motor, a drill steel operated thereby, a motor for feeding and rotating the drill steel comprising a cylinder

- and a piston, means for simultaneously admitting pressure fluid on each side of said piston and means responsive to resistance to rotation for interrupting admission of pressure fluid to one side of said piston and exhausting the pressure fluid therefrom.
9. In a drilling machine, a hammer motor, means for feeding said hammer motor to the work comprising a cylinder and a piston, means for simultaneously admitting pressure fluid on each side of said piston and means responsive to pressure conditions on one side of said piston for interrupting admission of pressure fluid to the said side of the piston and exhausting it therefrom.
10. In a drilling machine a hammer motor, a drill steel operated thereby, a single motor for feeding and rotating said drill steel, and means responsive to resistance to rotation for controlling the direction of movement of said single motor.
11. In a drilling machine having a drill steel therein, means for feeding and rotating the steel in one direction and means responsive to resistance to rotation for automatically reversing the direction of feed and rotation and thereafter resuming feed and rotation in the first direction.
12. In a rock drill of the hammer type, the combination of a single actuating means for feeding and rotating the drill steel, and means responsive to the resistance to rotation for automatically controlling said single feeding and rotating means.
13. In a drilling apparatus, a tool, a tool actuating motor, a motor for rotating said tool and feeding said tool actuating motor, and means comprising a valve responsive to variations of pressure within said second named motor for varying its operation.
14. In a drilling mechanism, work performing means comprising a percussive motor, a tool actuated thereby, a reversible motor for rotating said tool and feeding said percussive motor, and pressure fluid operated means responsive to work conditions for reversing said second mentioned motor.
15. In a drilling mechanism, a percussive motor, a tool operated thereby, a fluid pressure motor for rotating said tool and feeding said percussive motor, and pressure fluid operating means responsive to pressure changes in said second mentioned motor for reversing the direction of its movement.
16. In a drilling mechanism, a percussive motor, a tool actuated thereby, a fluid pressure motor for rotating said tool and feeding said percussive motor, and means having communication with said rotating and feeding motor, and automatically controlled by pressure changes in said motor for regulating the direction of the movement of said motor.
17. In a drilling mechanism, a hammer motor, a drill steel actuated thereby, a combined rotation and feeding means for effecting positive feed and rotation of the drill steel in either direction, and means responsive to drill steel rotation for automatically reversing said rotation and feeding means.
18. In a drilling apparatus, a percussive motor, a tool actuated thereby, a motor for rotating said tool and feeding said percussive motor, and means to control the operation of said feeding and rotating motor, whereby retraction from the work and reversal of rotation occur upon encountering abnormal work conditions.
19. In a drilling machine, a percussive motor, a drill steel operated thereby, a single motor for feeding and rotating said drill steel, means responsive to resistance to rotation for controlling the direction of movement of said single motor, and means permitting feeding without rotation of the steel.
20. In a drilling machine, a drilling tool, a drilling motor, a motor for feeding said drilling motor comprising a cylinder and a piston therein, a member having a screw arrangement with said piston whereby said member rotates upon relative movement between said cylinder and piston, and gearing connections between said member and said tool whereby said feeding motor causes rotation of the drilling tool.
21. In a drilling machine, a drilling tool, a drilling motor, a motor for feeding said drilling motor comprising a cylinder and a piston therein, a member having a screw engagement with said piston whereby said member rotates upon relative movement between said cylinder and piston, and gearing connections between said member and said tool including a clutch.
22. In a drilling machine, a drilling tool, a drilling motor, a motor for feeding said drilling motor comprising a cylinder and a piston therein, a member having reversible screw engagement with said piston whereby said member rotates in either direction upon relative movement in either direction between said cylinder and piston, connecting means between said drilling tool and said member, whereby the tool is rotatable with said member, and means responsive to resistance to rotation for controlling the operation of said feeding motor.
23. A machine for drilling holes having a frame, a tool carried thereby, means for rotating the tool and for feeding it to the work, said means including a cylinder and a hollow piston, a portion of the rotating means extending through said hollow piston, and means to alternate the direction of the tool feed when resistance to the tool is encountered.
24. A drilling machine including a drilling tool, means for feeding said tool, additional means for rotating said tool including a connection with said feeding means and extending therethrough, and automatic means for retracting the tool from the work when resistance is met by said tool during its operation.
25. A drilling machine including a drilling tool, means for feeding said tool to the work, additional means for rotating said tool including a connection with said feeding means and extending therethrough, and means for retracting the tool from the work when resistance is met by said tool during its operation and for resuming normal feed when the resistance has subsided.
26. A machine for drilling holes having a frame, a tool carrier thereby, fluid pressure means for rotating the tool and for feeding it to the work, said means including a cylinder and a hollow piston, a portion of the rotating means extending through said hollow piston, and fluid pressure means for reversing the direction of the tool feed when resistance to the rotation of the tool is encountered.
27. A drilling machine including a drilling tool, fluid pressure means for feeding said tool, additional means for rotating said tool including a connection with said feeding means and extending therethrough, and automatic pressure means for retracting the tool from the work.

when resistance is met by said tool during its operation.

28. A drilling machine including a drilling tool, fluid pressure means for feeding said tool to the work, additional means for rotating said tool including a connection with said feeding means and extending therethrough, and fluid pressure means for retracting the tool from the work when resistance is met by said tool during its operation and for resuming normal feed when the resistance has subsided.

29. In a drilling machine, a drill carried thereby, means for feeding said tool to the work including a cylinder and a hollow piston therein,

means for rotating said drill including an element extending through said hollow piston and having engagement therewith, and means for reversing the feeding direction controlled by the drill resistance to the work.

30. In a drilling machine, a drill carried thereby, fluid pressure means for feeding said tool to the work including a cylinder and a hollow piston therein, means for rotating said drill including an element extending through said hollow piston and having engagement therewith, and fluid pressure means for reversing the feeding direction controlled by the drill resistance to the work.

ANDREW T. DUPONT.
